A. HOLLANDER ET AL.

HOT OIL PUMP

Filed Sept. 21, 1925

UNITED STATES PATENT OFFICE.

ALADAR HOLLANDER, OF BERKELEY, AND ROBERT SCHURMAN, OF SAN FRANCISCO, CALIFORNIA, ASSIGNORS TO BYRON JACKSON PUMP MFG. CO., OF BERKELEY, CALIFORNIA, A CORPORATION OF CALIFORNIA.

HOT-OIL PUMP.

Application filed September 21, 1925. Serial No. 57,534.

In pumping oil under high pressure and temperatures, the greatest precaution must be observed to reduce the fire risk to a minimum.

5 Oil at high temperature flashes when brought in contact with air and thus any leakage into the air results in an immediate flash.

Provision must therefore be made in an 10 apparatus of this character to prevent all such leakage and flashing as far as this is possible, and also provision to quench any such flashing and to stop any leakages when they occur.

15 The operation of the pump involves generally the driving of an operating shaft by some suitable motor means located under atmospheric conditions of temperature and pressure, the said operating shaft passing 20 into a compartment of high pressure.

The gland structure which is employed to seal the high pressure chamber about the said operating shaft thus becomes a critically important element in such an apparatus, 25 the operation of the shaft not infrequently bringing about a wearing on the packing which occasionally results in a leakage from the high pressure compartment into the atmosphere. Such leakage is liable 30 to flash at once into flame and it is the object of our invention to confine said flashing within a chamber especially constructed for that purpose, and to provide said chamber with flame confining and flame extinguishing means and with gland adjusting means, 35 external to said chamber whereby the operator may, when such flashing occurs, quickly extinguish the flame and readjust the packing without interruption to the operation of 40 the apparatus or danger to himself.

A further object of our invention is the confining of such flashing within a specially constructed chamber to reduce fire risk to a minimum.

45 By referring to the accompanying drawings our invention will be made clear.

Fig. 1 is a vertical cross section through a high pressure hot oil centrifugal pump, driven by a direct connected steam turbine and embodying our invention.

50 Fig. 2 is a cross section in plan of the

flame protecting shield of Fig. 1, on the line II—II thereof.

Throughout the figures similar numerals refer to identical parts.

55 An oil pipe inlet is shown by the numeral 1, and a high pressure discharge port is shown at 2.

A centrifugal pump runner is indicated at 3 mounted upon a main driving shaft 4.

60 The latter is driven through the flexible coupling 5 from the conventional steam turbine 6, the runner picking up the oil from the inlet pipe 1 and passing the same under high pressure through the discharge pipe 2.

65 The pump casing 7 is supported by the frame structure 8 and base 9, the latter carrying also the steam turbine 6, thus securing alignment of all of the parts.

The bearing 10 is provided with a cover 70 and receiving pan 11.

Projecting below the upper edge of this 75 pan is the flame shield 12 having the hand plate 13 forming therewith a complete annular shell preferably conically shaped about the shaft 4 and extending upward beyond the lower limits of the collar member 14.

This collar member depends from the stationary portion of the frame structure 15 80 and is rotatably mounted in connection therewith, and adapted to be rotated by the pinion 16 actuated by the external hand wheel 17, carried on the spindle 18.

The collar 14 is provided with internal 85 threads 19 engaging exterior threads on the adjusting ring 20.

From the ring 20 connecting arms 21, 22 engage the gland 23.

The ring 20 slides upon the spline 24 and 90 is therefore longitudinally movable with respect to the stationary bearing member 25, but is prevented from rotation with the collar 14.

A rotating over-hanging skirt at 26 forces 95 a drainage into the pan 11 of any oil which may leak down the shaft 4.

Lubricating pipes are shown at 30, 31, 32, with conventional drains, pressure gauges, valves and accessory parts employed in the 100 operation of the pump.

Particular attention is directed to the

flame chamber 44 which is separated from the driving motor or steam turbine 6 by the diaphragm or partition 45, and to which access is had through the door 40.

- 5 In the event of flame developing within this chamber, it may be readily extinguished by the steam injector 35 more fully described below, and to enable the operator during such periods to approach, observe and bring
- 10 under control the abnormal conditions, there is provided a steam ejector at 42 supplied from the pipe 41 and discharging into a conventional discharge pipe 43 so that the vapors of combustion or other noxious fumes
- 15 or vapors may be ejected free from the doorway at 40 and in fact causing an in-draft in the chamber 44 when the door 40 is opened.

Our present invention is directed to minimizing the possible leakage from high pressure pump compartments into the atmosphere and the quenching of any flame resulting from the oil flashing when such leakage does occur and the readjustment of the parts to re-establish normal operation without interruption.

If, during the operation of the pump, oil accidentally leaks along the shaft 4, escaping by the gland packing material 33, it will flash when coming in contact with the air

- 30 and this flash will be confined within the chamber 44, and will appear as a flame at the bottom of the shield and about the pan 11.

The operator immediately opens the steam valve 34, supplying a jet of steam through the connecting pipe at 35 which quenches the flame.

The hand wheel 17 is now immediately rotated, actuating through the pinion 16, the rotation of the collar 14 and the raising of the adjusting ring 20, whereupon the arms 21, 22 force the gland 23 against the packing 33, forcing the packing tighter against the shaft and stopping the leakage.

The steam valve 34 is then closed and the apparatus continues without interruption.

While we have shown special forms of packing and gland and operating parts, a conically shaped flame shield, a stationary receiving pan 11 and other specific details of construction in the particular example chosen to exemplify our invention, it will be understood that variations in the forms and materials of these elements may be employed without departing from the spirit of our invention, and we wish to be understood as claiming all such variations.

We claim:

1. In a centrifugal pump, a shaft, gland means around said shaft adapted to prevent leakage of oil from the pump, motor means driving said shaft, a flame shield around said gland means and closed from said motor means.
- 60 2. In a centrifugal pump, a shaft, gland

means around said shaft adapted to prevent leakage of oil from the pump, motor means driving said shaft, a flame shield around said gland means and closed from said motor means, mechanism external to said shield constructed and adapted to adjust said gland means.

3. In a centrifugal pump, a shaft, gland means around said shaft adapted to prevent leakage of oil from the pump, motor means driving said shaft, a flame shield around said gland means and closed from said motor means and a steam injector to direct steam against an oil flame propagated adjacent said gland means.

4. In a centrifugal pump, a shaft, gland means around said shaft adapted to prevent leakage of oil from the pump, motor means driving said shaft, a flame shield around said gland means and closed from said motor means, mechanism external to said shield constructed and adapted to adjust said gland means and a steam injector to direct steam against an oil flame propagated adjacent said gland means.

5. In a centrifugal pump, the combination with a casing and an impeller within said casing, a driving shaft for said impeller and motor means actuating said shaft, of gland means in the casing wall and around the shaft constructed and adapted to prevent leakage of oil from the casing, a flame shield surrounding said gland means, a bearing and closure partition between said shield and said motor means.

6. The combination set forth in claim 5 and a steam port and valve to direct steam to extinguish flame adjacent the gland means.

7. The combination set forth in claim 5 and a steam port and valve to direct steam to extinguish flame adjacent the gland means and operating connections for said gland means external to said flame shield.

8. In a vertical shaft high pressure centrifugal pump, a driving shaft extending below the pump, motor means adapted to drive said shaft, a flame chamber between said pump and said motor means having an opening and closure means therefor, a hand operable flame shield around the shaft within the chamber.

9. The combination set forth in claim 8 and a steam port and valve constructed and adapted to direct a steam jet to extinguish flame adjacent the said shield.

10. In a centrifugal pump, the combination with a casing and an impeller within said casing, a driving shaft for said impeller and motor means actuating said shaft, of gland means in the casing wall and around the shaft constructed and adapted to prevent leakage of oil from the casing, a flame shield surrounding said gland means, a bear-

ing and a closure partition between said shield and said motor means, a flame chamber, and door means admitting access to said chamber.

5 11. The combination set forth in claim 5 and a steam port and valve to direct steam to extinguish flame adjacent the gland means forming a flame chamber, and door means admitting access to said chamber.

10 12. The combination set forth in claim 5 and a steam port and valve to direct steam to extinguish flame adjacent the gland means and operating connections for said gland means external to said flame shield, a flame chamber, and door means admitting access to said chamber.

15 13. In a centrifugal pump, the combination with a casing and an impeller within said casing a driving shaft for said impeller and motor means actuating said shaft, of gland means in the casing wall and around the shaft constructed and adapted to prevent leakage of oil from the casing, a flame shield surrounding said gland means, a bearing and 20 partition between said shield and said motor means, a flame chamber, and door means admitting access to said chamber, a discharge port from said chamber and a fluid ejector constructed and adapted to eject vapors from the chamber through said port.

25 14. The combination set forth in claim 5 and a steam port and valve to direct steam to extinguish flame adjacent the gland means, a flame chamber, and door means admitting access to said chamber, a discharge port from said chamber and a fluid ejector

constructed and adapted to eject vapors from the chamber through said port.

15. The combination set forth in claim 5 and a steam port and valve to direct steam to extinguish flame adjacent the gland means and operating connections for said gland means external to said flame shield, a flame chamber, and door means admitting access to said chamber.

40 16. In a vertical shaft high pressure centrifugal pump, a driving shaft extending below the pump, motor means adapted to drive said shaft, a flame compartment between said pump and said motor means having an opening and closure means therefor, a hand operable flame shield around the shaft within the compartment, a discharge port from said chamber and a fluid ejector constructed and 45 adapted to eject vapors from the chamber through said port.

50 17. In a vertical shaft high pressure centrifugal pump, a driving shaft extending below the pump, motor means adapted to drive said shaft, a flame compartment between said pump and said motor means having an opening and closure means therefor, a hand operable flame shield around the shaft within the compartment, a discharge port from said chamber and a fluid ejector constructed and 55 adapted to eject vapors from the chamber through said port, and a steam port and valve constructed and adapted to direct a steam jet to extinguish flame adjacent the said shield.
